DELIVERY OR EXTRUSION NOZZLE DEVICE

Raymond Harvey Anderson, Thornton Heath,
EnglandApplication October 16, 1936, Serial No. 106,003
In Great Britain February 22, 1936

5 Claims. (Cl. 221—60)

This invention comprises improvements in delivery or extrusion nozzle or cap devices such as are used upon a number of different containers. For example, such devices are applicable for use 5 on well-known collapsible tubes or containers, or on bottles such as hair cream bottles from which a fluid, powder or cream preparation may be delivered or expelled by shaking or by pressure applied by some means to the contents or on 10 sheet metal or other containers from which a fluid or any other content may be delivered or expelled by squeezing, shaking, or pressure application.

The object of my present invention is to provide 15 a closure device which can be readily manipulated by the fingers of the hand holding the collapsible tube or other container, and also will ensure a clean closure action obviating external accumulation of paste or other substance, according to the contents of the container, upon 20 the nozzle or cap, so that the cap or nozzle can be kept clean, whilst at the same time the opening and closing member will not unintentionally be freed from the cap or nozzle and thereby 25 become lost.

The present invention is broadly characteristic in that a cap or nozzle fitted to, or adapted to be fitted to, a container for paste, powder or liquid has a slideable shutter-like closure member 30 having an aperture adapted to be covered by the cap or nozzle for effecting a closure and to be exposed to effect an outlet opening, by to and fro sliding movement of said shutter, said shutter-like member and cap or nozzle being formed 35 with opposed abutment parts to limit the sliding movement of the shutter-like member.

The preferred form of this invention can be summarized as comprising a closure device, e. g. 40 a nozzle or cap, for a container such as a collapsible tube, bottle, liquid polish tin or the like, an extrusion or outlet orifice therein and a slideable closure member accommodated in and projecting beyond one side of the nozzle or cap, said 45 slideable closure member and the nozzle or cap being formed with parts adapted to abut against each other to permit the sliding movement of the slideable closure member, said slideable member and nozzle or cap having opposed edges normally contacting above said orifice to cover the 50 orifice.

In carrying the invention into practice I prefer to provide a nozzle device in the form of a cylindrical plug threaded internally or externally for fitting onto or into the neck of a collapsible 55 tube, bottle or other container, the said plug be-

ing hollow and formed with an integral flange at its top. This flange has an oblong or square part removed from it, the inner edge of the bay obtained by this cut away part coinciding with an orifice formed in the centre of a washer of 5 a compressible material e. g. such as cork or rubber fitted into the said plug and pressed between the rim of the neck of the collapsible tube, or other container, when the plug is threaded on to or into such neck. A slideable shutter 10 having a part the same width as said oblong or square removed part is passed diametrically through the top of the plug, and this shutter member is stepped at about midway between its ends to form a ledge to abut against the inner 15 edge of said bay, the uppermost surface of the shutter member being formed in a plane or shaped to lie in continuity with the upper surface of the said flange, so that when the shutter member is in the closed position there are no recesses in the top of the cap to trap paste or 20 other material extruded from the bottle. The slideable shutter like member normally projects beyond the said flange at the end remote from the part which lies in a plane in continuity with 25 the top of the flange, and this projecting end is formed with a shallow step located slightly within the periphery of the flange, and adapted to abut against the upper edge of a slot in one side of the plug, this slot slidably receiving the 30 shutter like member.

In order that my invention may be clearly understood and readily carried into effect I have appended hereto a sheet of drawings illustrating 35 embodiments thereof and wherein:—

Fig. 1 is a perspective view showing my invention applied to a collapsible tube, and with the cap closed.

Fig. 2 is a view similar to Fig. 1 with the exception that the cap is open.

Fig. 3 is a section through the cap taken along the slideable closure member, the latter being in the closed position.

Fig. 4 is a view similar to Fig. 3 but with the slide open.

Fig. 5 is a perspective view showing a concave faced flange to the cap and with the slideable member closed.

Fig. 6 is a perspective view of the slideable closure member.

Fig. 7 is a perspective view of the cap without the slideable closure member.

Fig. 8 is a perspective view showing the invention applied to supporting a pair of containers.

so that e. g. alternative forms of paste are readily available for use.

Fig. 9 shows in section and perspective suitable mould elements for moulding a quantity of caps simultaneously.

Fig. 10 is a detail sectional view in perspective showing the die and matrix engaged and a mould slide pressed home to produce in the moulded article a slot to receive the slidable closure member, and

Fig. 11 is a detail section taken at right angles across the said mould slide.

Referring to the drawing the cap device is shown as applied to a collapsible tube, but it is equally applicable to bottles and sprinkler containers, e. g. tins for liquid polishes or powders. It consists of a stem or plug portion 1 in the form of a hollow cylinder threaded internally as at 2 in Fig. 3 for attachment to the threaded neck 20 of a collapsible tube 4. Integral with this cylindrical neck is a flanged top 5, the upper surface of which may be convexly or concavely curved as shown in Figs. 1 and 5 respectively, or it may be a plane surface. The periphery of this flange 25 may be polygonal, circular or other suitable ornamental shape. The stem 1 is slotted diametrically at its upper end, and the slot 6 is partly, or may be wholly contained within the lower face of the flange 5.

30 Fitted into the slot 6 is a bar like slide 7 the lower face 8 of which is a single plane face against which is tightly pressed a washer 9 of cork, rubber or other suitable material interposed between the slide 7 and the rim of the threaded neck 3 of the container 4. It will be seen that by tightly threading the stem 1 upon the neck 3 that the slide 7 will be frictionally gripped within the cap and therefore will not be sufficiently loose to slide unintentionally. The upper face of 40 the slide 7 is formed for about half its length with a thickened part 7a, the longitudinal vertical walls of which are stepped narrowly inwardly relatively to the base part of the slide as indicated at 7b. This thickened part 7a forms an oblong or square block which fits accurately within a correspondingly shaped bay or opening 10 cut in the flange 5, the inner edge 10a of this opening 10 being disposed immediately above a central orifice 9a formed in the washer 9. Normally the inner vertical wall 7c of the block 7a abuts against the said inner edge 10a of the opening 10 consequently a close sealing action is obtained preventing extrusion of the contents of the container. When it is desired to extrude 50 such contents the slide is pushed in the direction required to separate the opposed edges 7c and 10a. This push is effected by pressing in the end 7d of the slide 7 which is remote from the block 7a, such end 7d normally projecting a slight distance beyond the periphery of the flange 5 so as to be accessible for such purpose. A short distance from this end 7d the upper face of the slide 7 is very shallowly stepped downwards as at 7e to afford an abutment adapted to engage 60 against a corresponding step 6a formed in the slot 6. By this means the slide 7 cannot be completely pushed through the cap and will not be lost. This is an advantage over existing caps which have to be removed to enable the contents 65 of the container to be extruded.

The pushing in of the end 7d of the slide brings opposite the orifice 9a an aperture 7f in the slide. This aperture is normally spaced from the orifice 9a. The aperture 7f is preferably of 70 oblong form as shown when the device is intended

for use with a tooth paste tube, as by this means a ribbon of paste can be extruded on to the top of the flange 5. However a circular or other suitably shaped aperture may be adopted.

The amount of sliding movement imparted to the slide need only be quite small, e. g. one tenth of an inch for use with a tooth paste tube, and this results in the slide being firmly supported when in the open position.

The upper surface of the block 7a is shaped so as to be in continuity with the upper surface of the flange 5 so that when the slide is closed there are no external crevices within which paste or other material is trapped. Also the action of closing the slide will cleanly sever the ribbon of 15 paste, and a tooth brush, shaving brush, polishing rag or other utensil can wipe off the extruded paste cleanly from the flange without waste and without leaving any deposit on the flange.

The formation of the slots 6 in the caps when 20 being moulded can be effected by sliding plates 12 through the walls of the female element 13 of the mould as shown in Figs. 9, 10, and 11. The openings 10 in the flanges can be effected by forming raised block-like parts 14 in the depressions 15 in which the flanges 5 are moulded. The male element 16 of the mould carries a plurality of bosses 17 adapted to enter corresponding recesses 18 of the female part 13, these bosses 17 being concentrically recessed as at 19 to form the 30 stems 1 of the caps.

The present invention obviates the need for a slot or port in the cap, in which slot or port cream or liquid can remain exposed to the air and to pollution by atmospheric impurities. The device 35 is therefore thoroughly hygienic, because no portion of the cream or liquid preparation can be deteriorated or rendered impure or septic by exposure.

In some cases, it may be desired that an end 40 of the slide shall not project when the latter is in the closed position. To satisfy this demand, the diameter of the disc may be increased and the periphery of the disc may be notched, so that the end of the slide, which otherwise would project, resides in this notch, or, the disc may be formed with a recess in its thickness so that the end of the slide, when in the closed condition, will be completely housed within the disc and not exposed to damage or breakage. By the construction above described, the slide is perfectly guided and stopped and prevented from any movement other than a sliding movement. Should the slide become damaged and jammed by extremely rough usage, it is nevertheless possible 55 to unscrew the fitting in order to obtain discharge of the contents of the container.

The flange 5 can be eliminated by having a thicker stem portion 1, the top of the cap having its edge bounded by the periphery of the stem 60 portion 1. This would be suitable for caps for bottles.

What I claim is:—

1. A cap or nozzle for use on a container comprising a body part adapted to be fitted to a container, a slidable shutter-like closure member slidably transversely through the body part, an aperture in said slidable member between its ends normally covered by the top of the said body part, an opening in the top of the body part 70 with which the aperture in the slidable member is brought into and out of registration by to and fro sliding movement of said slidable member, a pair of abutments on said slidable member, one of which is near the aperture in the slidable 75

member and normally engaged against an edge of said opening in the top of the body part, the other abutment serving as a stop to limit the opening sliding movement of the slidable member.

5 2. A cap or nozzle for use on a container comprising a body part, an opening in said body part, a slidable closure member accommodated in said body part and having a projecting part one side of the body part adapted to be engaged for pushing the slidable closure member to the open position, co-operating abutments on said slidable closure member and the body part adapted to abut against each other to limit the opening sliding movement of the slidable closure member, an upstanding part on the upper face of said slidable member slidable in the said opening in the body part, an extrusion orifice in said slidable member, said upstanding part and said opening having opposed edges normally contacting above said orifice to close the orifice.

3. A cap or nozzle for use on a container comprising a body part in the form of a tubular stem part adapted to be attached to the neck of the container, a head formed at the upper end of said stem, an opening cut into said head and a slot formed diametrically or transversely horizontally through the body part in continuity with said opening, a slide slidably accommodated in said slot and opening, a thickened part on said slide projecting upwardly in said opening, the upper face of said thickened part being formed in continuity with the upper surface of said head, said thickened part normally filling said opening, an abutment on the upper surface of said slide adjacent to the end remote from the thickened part, an abutment in said head adapted to be engaged by the before-mentioned abutment to limit the sliding movement of the slide, an opening in said slide between said thickened part and said abutment, and a washer like member fitted in the stem and adapted to be pressed against the base of the slide by the rim of the neck of the container.

45 4. A cap or nozzle for use on a container comprising a body part in the form of a tubular stem part adapted to be attached to the neck of the container, a flange like head formed at the upper end of said stem, an opening cut into said head and a slot formed diametrically or transversely

horizontally through the junction of the said head and stem in continuity with said opening, a slide slidably accommodated in said slot and opening, a thickened part on said slide projecting upwardly in said opening, the upper face of said thickened part being formed in continuity with the upper surface of said head, said thickened part normally filling said opening, an abutment on the upper surface of said slide adjacent to the end remote from the thickened part, an abutment on the lower face of said head adapted to be engaged by the before-mentioned abutment to limit the sliding movement of the slide, an opening in said slide between said thickened part and said abutment, and a washer like member fitted in the stem and adapted to be pressed against the base of the slide by the rim of the neck of the container.

5 20 5. A cap or nozzle for use on a container comprising a body part in the form of a tubular stem part adapted to be attached to the neck of the container, a head formed at the upper end of said stem, an opening cut into said head and a slot formed diametrically or transversely horizontally through the body part in continuity with said opening, a thickened part on said slide projecting upwardly in said opening, a slide slidably accommodated in said slot and opening, a thickened part on said slide projecting upwardly in said opening, the upper face of said thickened part being formed in continuity with the upper surface of said head, said thickened part normally filling said opening, an abutment on the upper surface of said slide adjacent to the end remote from the thickened part, an abutment on the upper surface of said slide adjacent the end remote from the thickened part, an abutment in said head adapted to be engaged by the before-mentioned abutment to limit the sliding movement of the slide, an opening in said slide between said thickened part and said abutment, and a washer like member fitted in the stem and adapted to be pressed against the base of the slide by the rim of the neck of the container, the upper surfaces of said head and said thickened part of the slide lying in continuity with each other to obviate steps or depressions at their opposed abutting parts when the slide is closed.

RAYMOND HARVEY ANDERSON. 50
